UNITED STATES PATENT OFFICE.

JONAS NORTHROP, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

SPECIFICATION forming part of Letters Patent No. 697,004, dated April 8, 1902.

Application filed July 8, 1901. Serial No. 67,437. (No model.)

To all whom it may concern:

Be it known that I, JONAS NORTHROP, a subject of the King of Great Britain, residing at Hopedale, county of Worcester, State of Massachusetts, have invented an Improvement in Automatic Filling-Replenishing Looms, of which the following description, in connection with the accompanying drawings, is a specification, like numerals on the drawings representing like parts.

This invention has for its object the production of an automatic filling-replenishing loom containing various novel features of construction, arrangement, and operation, as will more fully appear hereinafter.

One of the novel features of my invention consists in effecting the actuation of the filling-replenishing mechanism by or through the proper boxing of the shuttle when the filling breaks, the device which becomes operative upon such occurrence being mounted on the shuttle itself.

Other novel features will be fully described in the specification and particularly pointed out in the claims.

Figure 1 is a right-hand side elevation of a portion of a loom embodying my invention, the lay and filling-feeder being shown in transverse section. Fig. 2 is a top or plan view of the inner end of the lay or the end at which change of filling is effected, the shuttle-box and a shuttle being shown and also a part of the means for controlling the operation of the filling-replenishing mechanism. Fig. 3 is a top or plan view of the opposite or outer end of the lay and the shuttle-box thereon, the left-hand end of the breast-beam, and a portion of the means for suspending the action of the take-up mechanism. Fig. 4 is a top or plan view of one end of the shuttle, enlarged, with the threading device and the actuator controlled by the filling while intact. Fig. 5 is a transverse sectional view of Fig. 4 on the line αx , Fig. 4; and Fig. 6 is a left-hand side elevation, in part, of the loom, the mechanism shown in plan Fig. 3 being herein illustrated in side elevation.

Of the filling-replenishing mechanism herein illustrated it will be necessary to state that it comprises a filling-feeder 1 to contain a series of filling-carriers 2 to be removed there-

from one by one at the proper time by the transerrer 3 and inserted in the shuttle, which is open top and bottom to receive the fresh supply of filling and permit the ejection of the spent filling-carrier in well-known manner. The transerrer is fulcrumed at 4 on a stand 5, secured to the breast-beam 6 at or near one side of the loom, and a depending arm 7 on the transerrer has mounted thereon a dog 8, notched at its rear end to be at times engaged by a bunter 9 on the lay 10, such engagement acting as the lay beats up to rock the transerrer and effect a transfer of filling, all substantially as in United States Patent No. 529,940, to which reference may be had. A rock-shaft 11 is mounted in the lower end of the arm 7, and the dog 8 is secured to said rock-shaft, its downward movement being limited by a stop-pin 12, mounted on the dog 7 and extended across the front face of the arm 7. (See Figs. 1 and 2.) The rock-shaft has an L-shaped arm 13, the longer portion of which is parallel to the lay and extended toward it to be engaged by suitable means, to be described, to turn the dog in the direction of arrow 14, Fig. 1, and into the path of the bunter 9. At its inner end—i. e., the one nearest the filling-replenishing mechanism—the lay is provided with a shuttle-box 15 of usual construction, except that its front wall 16 is provided with an aperture 17 to receive the in-turned end of a cam-foot 18, secured to a dagger 19, mounted to rock on an upright stud 20 on the lay in front of the shuttle-box. The dagger is so located relatively to the long part of the arm 13 that when the former is in dotted-line position, Fig. 2, it will engage and elevate said arm as the lay beats up, thereby operatively position the dog 8, the free end of the dagger being bent (see Fig. 1) to constitute a species of cam-surface upon which the horizontal part of the arm 13 slides to be lifted thereby. As shown in Fig. 2, the dagger is mounted near the outer end of the shuttle-box 15, with the foot 18 normally projecting beyond the inner face of the front wall 16, a spring 21 maintaining the foot and dagger in the position shown.

I have herein provided means carried by the shuttle and rendered operative by or through breakage or exhaustion of the fill-

ing to automatically effect a change of filling on the pick, which effects the entrance of the shuttle into the inner shuttle-box when the breakage or exhaustion of filling is detected 5 on such pick of the shuttle.

Referring now to Figs. 2, 4, and 5, the shuttle 22 has an elongated opening 23 extended therethrough from top to bottom, as is common in self-threading shuttles, to contain a 10 supply of filling 2 when transferred thereto from the feeder 1, and at one end the shuttle is provided with a self-threading device to conduct the thread automatically to the side-delivery eye 24 of the shuttle. The 15 threading device herein illustrated is substantially that forming the subject-matter of United States Patent No. 556,705, dated March 17, 1896, the block 25 having a thread-passage 26, Fig. 4, provided with a longitudinal entrance 27, a downturned spur 28 preventing accidental withdrawal of the thread from the passage 26, the thread passing between the top of the shuttle and the curved edge 29 of the threading-block to the delivery-eye, as in said Patent No. 556,705. I have mounted a downhold on the shuttle-body just back of the threading-block, consisting of a downturned hook 30, Fig. 5, opposite the inner end of the thread-passage 26 25 and secured to or forming part of an upright post 31, bent at its upper end to engage the threading-block and at its lower end inserted in the wood of the shuttle. Between the post and the block I have mounted an actuating 30 device comprising a body portion or actuator proper, 32, fulcrumed at 33 on a suitable stud and having a detecting-finger 34, the said device being adapted to rock in a plane transverse to the longitudinal axis of the shuttle. 35 The actuator 32 is extended laterally through a slot 35 in the side of the shuttle, and when in full-line operative position, Fig. 5, the actuator projects beyond the side of the shuttle, which latter is grooved longitudinally, as at 36. 40 When the threading of the shuttle is effected, however, the thread between the block 25 and the filling-carrier 2 engages and presses down the finger 34 and lifts the actuator into dotted-line position, Fig. 5, so that the actuator is 45 above the groove 36, and the thread slips down under the hook-like downhold 30, and so long as the filling-thread is intact it will maintain the actuator in inoperative dotted-line position. Breakage or exhaustion of the 50 filling, however, releases the finger, the actuator drops into full-line position, Fig. 5, the body portion 32 being the heavier, and the projecting part in the groove 36 will be in position to engage the foot 18, Fig. 2, and 55 60 as the shuttle reaches the end of its shot and is properly boxed in the inner shuttle-box 15 the actuator will have pushed the foot outward, and thereby swung the dagger 19 into operative dotted-line position, Fig. 2, to engage the arm 13 as the lay beats up, as has been referred to, and filling-replenishing will be effected on that beat of the lay. The foot

18 enters the groove 36 at every alternate pick, but normally the actuator will be held up above it, so as to cause no effective movement of the dagger; but whenever the filling has broken or run out the replenishing mechanism will be operated by the proper boxing of the shuttle in the inner box. 70

If the shuttle is improperly boxed, the filling will not be replenished, because the final movement of the shuttle for a short distance after engagement of the actuator and dagger-foot 18 is absolutely necessary to operatively position the dagger, and such final movement is not present when the shuttle fails to complete fully its stroke. 75

The operation of the take-up mechanism need not be suspended under the foregoing conditions; but should the filling fail on the shot of the shuttle to the left or to the outer shuttle-box 37, Figs. 3 and 6, then the filling cannot be replenished until the second pick thereafter, and unless the take-up is suspended thin places will be made in the cloth. 80 90

Of the take-up mechanism I have shown only the ratchet-wheel 38, the take-up pawl-carrier 39, having a lateral lug 40 thereon, and two let-back pawls 41 and 42, to operate successively in well-known manner, the 95 longer pawl 41 rocking on a fulcrum 43, supported on the loom-frame, while the shorter pawl 42 is longitudinally slotted at 44 to embrace and slide on the stud 43 when pawl 41 is raised sufficiently to disengage it from the ratchet-wheel, the construction and operation being substantially as in United States Patent No. 643,284, dated February 13, 1900. As in said patent, the pawl-carrier has a locking-shoulder 46 to at times engage a lateral 100 stud 45 on the pawl 41, the normal position of the parts being shown in Fig. 6. The shipper 47, normally held in the usual notched plate 48 while the loom is running, is the only part shown of the usual stop-motion 110 actuated by release of the shipper to stop the loom, and a knock-off lever 49 50 is fulcrumed at 51 on the breast-beam 6 to effect automatically the release of the shipper. The inner end 50 of the lever extends behind 115 a latch 52, pivoted at its outer end at 53 to an upturned arm 54, fulcrumed on a rod 55, suitably secured to the loom-frame and having a depending extension 56, which projects immediately in front of the let-back pawl 42 120 when the latter is in its normal position herein illustrated. A spring 57 (see Fig. 3) is rigidly held at one end and at its other end is secured to the hub of the arm 54 to maintain the extension 56 against the pawl 42, and the latch has a lateral ear 58, and at its inner end it is downturned or hooked, as at 59. A second upturned arm 60 is fulcrumed on the rod 55, and it also has a depending extension 61 to at times coöperate with the lug 130 40 on the pawl-carrier of the take-up mechanism, while at its upper end the arm 60 has pivoted to it at 62 an arm 63, extended rearwardly across the breast-beam and having se-

cured to or forming part of it a cam-like latch-detent 64 to coöperate with the ear 58 on the latch, and a bunter 65 at its top downwardly inclined, as at 66, from front to rear and substantially in the path of movement of the latch 52. The front wall 67 of the outer shuttle-box 37 is slotted at 68 to admit an inwardly-extended trip 69, fast on a slide-rod 70, mounted in suitable bearings 71 on the lay, and held in the position shown in Fig. 3 by a spring 72, interposed between one of the bearings and a collar 73, fast on the slide-rod. The inner end of the latter has secured to or forming part of it a bunter 74, which is normally at one side of the rearwardly-extended arm 63. Now if the actuator 32 is operatively positioned when the shuttle enters the outer shuttle-box said actuator will engage the trip 69 and will move the same in the direction of the arrow 75, Fig. 3, as the shuttle reaches the outer end of its stroke, supposing that the shuttle is properly boxed, and such movement of the slide-rod 70 will move the bunter 74 into position to engage the arm 63 as the lay beats up, and to thereby swing outward the upturned arm 60. When this results, the depending extension 61 will act upon the lug 40 to move the pawl-carrier 39 to disengage the actuating-pawl from the ratchet-wheel 38, and at the same time the projection or lug 45 will be engaged by the pawl-carrier to disengage the pawl 41, permitting the pawl 42 to let back or permit retrograde movement of the ratchet-wheel in the direction of the arrow 76. As the let-back pawl 42 is thus moved to the right or outwardly, viewing Fig. 6, it acts upon the extension 56, swinging it outward and necessarily swinging inwardly the upturned arm 54, so that the latch 52 is moved back until its hooked end 59 is over and back of the inner arm 50 of the knock-off lever. When the bunter 74 has moved the arm 63 out, as has been described, the latch-detent 64 will have been withdrawn from beneath the ear 58, permitting the latch to drop with its hooked end in front of the arm 50; but before the rearward movement of the latch just described takes place the inward movement of the arm 63 to normal position is effected, and the ear 58 slides up onto the latch-detent, so that the latch can pass over the detent-arm when it is moved rearwardly by or through the movement of the let-back pawl 42. This suspension of the operation of the take-up mechanism provides for the necessary number of picks which occur before the shuttle can be thrown to the inner shuttle-box to effect a change of filling, so that thin places in the cloth will be prevented by thus suspending the take-up.

It sometimes happens that the shuttle will fail to thread after a fresh supply of filling has been inserted therein, and it is then necessary to stop the loom, and for this purpose I have provided the latch and the latch-bunter 66.

If the operation just described has taken place by the entrance of the shuttle in the outer shuttle-box 37, suspending the action 70 of the take-up and effecting the movement of the latch 52 into such position that its hooked end 59 will be behind the arm 50 of the knock-off lever, then supposing that at the right-hand shot the filling is inserted in the shuttle and fails to thread, the actuator 32 will therefore remain operative on the next or third shot of the shuttle to the left, and a second time successively the bunter 74 will be moved into position to move the arm 63 outward, and this second movement takes place when the downturned end or hook 59 is in the path of the bunter 65 and between the latter and the knock-off arm 50, so that on the second outward movement of the arm 63 the bunter 65 will press against the hooked end 59 of the latch 52, and it in turn will operate to swing the knock-off lever to release the shipper, so that the loom will be automatically stopped. It will be noted that the first time 90 the arm 63 is moved out the downturned hook 59 will drop onto or back of the bunter 65, and in order to permit the passage of the bunter beneath the hook as the former returns to its normal position I have inclined the upper face or top of the latch-bunter, as at 66, so that when the arm 63 moves inward the hook will slide up the incline 66 and when released therefrom the ear 58 will drop onto the latch-detent 64.

It will be obvious that when the extension 61 is permitted to return to normal position, as it will by the weight of the take-up-pawl carrier acting thereupon, the said pawl-carrier will return to its normal position, so that 105 the take-up pawl will reengage with the latch-wheel 38, and the interrupted operation of the take-up will be resumed. So, too, the spring 57 acts to not only keep the extension 56 against the let-back pawl 42, but also assists 110 in returning such pawl to its normal position, aided and assisted by the rotation of the ratchet-wheel opposite to the arrow 76.

I have herein illustrated my invention in connection with mechanism for inserting a 115 fresh supply of filling in a running-shuttle when the previous supply breaks or runs out.

I have herein shown and described a novel form of shuttle adapted to be used in connection with a loom of the type illustrated and described; but I do not claim herein the shuttle *per se*, as it forms the subject-matter of another application, Serial No. 93,874, filed February 13, 1902.

Having fully described my invention, what 125 I claim, and desire to secure by Letters Patent, is—

1. In a loom, the lay, an automatically self-threading shuttle adapted to contain a supply of filling, a normally inoperative actuator mounted on the shuttle and having a finger transverse to the path of and automatically engaged by the filling when a fresh supply is inserted in the shuttle, and a body adapt-

ed to project laterally beyond the shuttle side when breakage or exhaustion of the filling releases the finger, filling-replenishing mechanism, to insert a supply of filling in the shuttle and means to control its operation, including a dagger pivotally mounted on the lay and having a part in the path of the actuator-body when the latter is operative, to move the dagger into operative position by the shuttle as it reaches the end of its throw.

2. In a loom, the lay, a shuttle, a filling-carrier therein with a supply of filling, a normally inoperative actuator mounted on the shuttle, controlled by the filling-thread between the filling-carrier and the shuttle-eye and movable into operative position by breakage or exhaustion of the filling, filling-replenishing mechanism, located at one side of the loom, and means to control the operation of said mechanism, including a dagger mounted on the lay at the end adjacent said mechanism, the actuator when operatively positioned engaging and rendering the dagger operative by the completion of the shuttle movement into the adjacent shuttle-box, and a dog moved into active position by the dagger at such time as the lay beats up.

3. In a loom, the lay, a shuttle adapted to receive a supply of filling, a device at one end of and to thread the shuttle automatically when filling is inserted, an actuator mounted on the shuttle adjacent the threading device and automatically engaged and normally held inoperative by the filling while intact, mechanism to automatically insert a supply of filling in the shuttle, and means to control its operation, including a dagger mounted on the lay and having a part in the path of the actuator, if operatively positioned by or through breakage or exhaustion of the filling, engagement of the dagger and actuator rendering the former operative when the shuttle has been completely boxed.

4. In a loom, the lay, an automatically self-threading shuttle adapted to contain a supply of filling, an actuator on the shuttle, having its outer end movable in a slot in the side wall of the shuttle and automatically engaged and maintained in inoperative position by the filling while intact, a filling-feeder, a trans-ferrer, means to operate it to transfer a supply of filling from the feeder to the shuttle, said means including a normally inoperative dog, and positioning devices for the dog, actuated by or through the actuator when in abnormal, operative position, as the shuttle completes its throw and is properly boxed at the end of the lay adjacent the filling-feeder.

5. In a loom, the lay, an automatically self-threading shuttle adapted to contain a supply of filling, a tilting actuator mounted on the shuttle and having its inner end extended across the filling-thread and automatically engaged thereby upon entrance of a fresh filling-supply, and having its outer end extended through an opening in the shuttle side, said actuator being maintained inoperative

by the intact filling, filling-replenishing mechanism at one side of the loom, to insert a fresh supply of filling in the shuttle, a shuttle-box 70 on the adjacent end of the lay, having an aperture in its front wall, and controlling means for the said mechanism, including a dagger pivotally mounted on the lay and having a foot extended through the aperture in the 75 shuttle-box wall, the actuator when released by breakage or exhaustion of the filling engaging the foot as the shuttle reaches the end of its throw, thereby turning the dagger into position to cause the operation of the filling-replenishing mechanism as the lay beats up.

6. In a loom provided with filling-replenishing mechanism, means for controlling its operation, including a dagger on the lay, and a dog having an arm to be engaged by the dagger to operatively position the dog, the lay, a bunter thereon to engage the dog when operatively positioned, and effect operation of the filling-replenishing mechanism on the forward beat of the lay, a shuttle adapted to 90 contain a supply of filling, and an actuator mounted thereon and maintained inoperative by intact filling, release of the actuator causing it to engage and operatively position the dagger as the shuttle reaches the end of its throw at the same end of the lay.

7. In a loom, filling-replenishing mechanism located at one side of the loom, means to control its operation, including a dagger mounted on the lay at the end thereof adjacent said mechanism, a take-up, the lay, a shuttle adapted to contain a supply of filling, an actuator mounted thereon and maintained inoperative by intact filling, and means, to prevent operation of the take-up, including 105 a movable bunter mounted on the lay at the end farthest from the replenishing mechanism, the shuttle when properly boxed at the replenishing side of the loom acting through the actuator if the latter is in operative position, to move the dagger to effect actuation of the replenishing mechanism on the same pick, and to prevent the operation of the take-up when the shuttle is properly boxed at the opposite end of the lay.

8. In a loom, filling-replenishing mechanism located at one side of the loom, means to control its operation, take-up mechanism, the lay, a shuttle adapted to contain a supply of filling, and devices to suspend normal operation of the take-up mechanism and permit let-back, actuated by or through proper boxing of the shuttle at the outer end of the lay, if the filling fails or is exhausted, the proper boxing of the shuttle, under the same conditions, at the inner end of the lay, adjacent the replenishing mechanism, effecting the operation of the controlling means to cause the actuation of the filling-replenishing mechanism.

9. In a loom, a stop-motion therefor, filling-replenishing mechanism, means to control the operation thereof, take-up mechanism, the lay, a self-threading shuttle adapted to contain a supply of filling, an actuator car-

ried by the shuttle and maintained inoperative by intact filling, the actuator when inoperative position coöperating with the controlling means to effect actuation of the replenishing mechanism as the shuttle reaches the end of its stroke in one direction, a device to coöperate with the actuator when operatively positioned, as the shuttle completes its stroke in the opposite direction, to suspend the operation of the take-up mechanism, and means operative by or through two successive operations of said device to effect the actuation of the stop-motion for the loom, whereby the loom will be stopped automatically if the shuttle fails to thread after the operation of the filling-replenishing mechanism.

10. In a loom, filling-replenishing mechanism, means to control the operation thereof, take-up mechanism, including a let-back pawl, means to suspend the operation of said mechanism and permit the let-back pawl to operate, said means including an arm having a detent and a latch-bunter thereon, a shipper, a knock-off lever therefor, a latch normally held inoperative by the detent, means controlled by operation of the let-back pawl to release the latch from the detent and move

the former into position to actuate the knock-off lever, after the first operation of the take-up-suspending means, a shuttle adapted to contain a supply of filling, and an actuator carried thereby and normally maintained inoperative by intact filling, the actuator when released by filling failure coöperating with the controlling means to effect filling replenishing as the shuttle reaches the end of the stroke in one direction, said actuator, when operatively positioned, effecting the operation of the means for suspending action of the take-up as the shuttle completes its stroke in the opposite direction, the successive operation of said take-up-suspending means moving the arm thereof to bring the latch-bunter into engagement with and to move the latch and thereby the knock-off device to release the shipper.

In testimony whereof I have signed my name to this specification in the presence of two subscribing witnesses.

JONAS NORTHRUP.
